BOTTLE

Robert J. Donoghue, 900 Windsor Ave.,
Windsor, Conn. 06095

Filed Sept. 8, 1970, Ser. No. 24,875

Term of patent 14 years

Int. Cl. D9—01

U.S. Cl. D9—131

FIG. 1

FIG. 4

FIG. 2

FIG. 5

FIG. 3

FIG. 1 is a top plan view of a bottle embodying my new design;

FIG. 2 is a side elevational view, the opposite side being a mirror image of the side shown;

FIG. 3 is a bottom plan view;

FIG. 4 is a top plan view with the closure cap removed; and

FIG. 5 is a vertical sectional view taken on line 5—5 of FIG. 4.

I claim:

The ornamental design for a bottle, substantially as shown and described.
